SLACK-ADJUSTER FOR RAILWAY-BRAKES

1,136,620.

Specification of Letters Patent.

Patented Apr. 29, 1915.

Application filed June 29, 1908, Serial No. 440,931. Renewed June 15, 1912. Serial No. 703,975.

To all whom it may concern:

Be it known that I, WILLIAM H. SAUVAGE, a citizen of the United States, and a resident of the borough of Manhattan, city, county, and State of New York, have invented certain new and useful Improvements in Slack-Adjusters for Railway-Brakes, of which the following is a specification.

My invention relates to devices for taking up the slack in brake mechanism for railway cars, or vehicles of any character, and has for one of its objects to provide a very simple device, working automatically and requiring no skilled labor for its initial adjustment or readjustment at any time.

Other objects will be in part obvious and in part pointed out hereinafter.

One of the features of my invention is the particular construction of the brake beam 20 combined with a slack adjuster whereby a very strong and compact construction is obtained.

Various forms of my invention are illustrated in the accompanying drawings, in 25 which—

Figure 1 is a diagrammatic section illustrating the application of my invention to a railway truck; Fig. 2 is a similar view showing another form of my invention; Fig. 3 shows a third form; Fig. 4 is a perspective view of one of the parts employed in the construction of Fig. 3; Fig. 5 is a top plan view of a truck with certain levers in section on line 5—5 of Fig. 2; Figs. 6 and 7 35 illustrate still other forms of my invention in longitudinal section; Fig. 8 is a horizontal section on line 8—8 of Fig. 7; Fig. 9 is a longitudinal section of a truck provided with still another form of my invention; 40 Figs. 10 and illustrate other forms of slack adjuster in longitudinal section and Fig. 12 shows still another form of my invention partly in longitudinal section.

Similar reference characters refer to similar parts throughout the several views of the drawings.

In the construction illustrated by Fig. 1, the car wheels A—A' are adapted to be engaged by the brake shoes B—B' carried by 50 the brake beams C—C' respectively. These beams are hollow in the particular construction shown and each provided at its central portion with an arm D—D' extending lengthwise of the car toward the adjacent 55 axle. The live lever E is pivotally connected

at E' with the arm D and at E with the rod F, by means of which the braking power is applied in any suitable manner. At its lower end E' the live lever is connected by a rod G with the lower end of the dead lever H, fulcrumed at H' upon a bracket J suitably secured to a bolster J'. The bracket J may be provided with a series of holes J², so that the fulcrum pin H' may be differently adjusted as desired. It is of course 60 understood that this adjustment is made once for all and is generally not altered when made. The arm D' is provided with a slot D² in which is adapted to move a pin H² projecting from the dead lever H and 70 connecting it with a slide K movable along the arm D', said slide being guided partly by the pin H² and partly by a second pin K' also adapted to move in the slot D². At the end of the arm D' is located an inclined 75 bearing D³ for the toothed face L' of a wedge L adapted to slide between the members of the arm D', which for this purpose is forked, being similar in this respect to the construction shown in Fig. 5. The 80 wedge is held between the inclined face D³ and the pin K'. The downward movement of the wedge is limited by a flange L² at its upper edge while any upward movement of the wedge (as when it is knocked upward 85 with a hammer or other tool) is limited by a hook-like projection of the lower edge of the wedge and if desired a pin L³. It will be understood that the wedge has a tendency to slide downward and will so move if the 90 pin K' is carried to the left in Fig. 1. The brake beam C' is provided with a guide C² forming a bearing for a take-up rod M, the left-hand end of which is provided with a slot M' to receive the pin E'. The other end 95 of the rod M is adapted to be engaged by a perforated dog N, fulcrumed at N' upon a small bracket projecting from the arm D' and pressed away from the bracket C' by means of a spring O.

When the brake is applied by a pull exerted by the rod F toward the left, the live lever E first swings about the point E' as a fulcrum to bring the brake shoe B against the wheel A and then the point E' serves a fulcrum for the live lever E so that the rod G is moved toward the right carrying the dead lever H and the brake shoe B' in the same direction. This is the usual operation of a car brake. As long as the parts are

properly adjusted, this operation will not effect the adjustment of the take-up rod M^2 , relatively to the bearing C^2 . This is due to the fact that the length of the slot M' is such as to correspond to the normal travel of the fulcrum pin E' in the ordinary application of the brake. If however, the brake shoes have worn to a certain extent, so that when the lever E swings toward the left, the pin E' will not only reach the end of the slot M' , but will further exert a pressure against the rod M , it will be seen that the dog N will allow the rod M to slide in its bracket or bearing C^2 , the length of this sliding movement being exactly equal to the length of the excess movement of the pin E' , or, in other words, to the slack existing in this part of the apparatus. It will be seen that this adjusting movement increases the distance between the brake beams. During the release movement of the brakes the pin E' will have only its normal travel, that is, a travel equal to the length of the slot M' if the position of the rod M has not been changed during the application of the brakes. If, however, during the release movement the lever E travels a greater distance than the length of the slot M' at the pin E' , then as soon as the pin E' engages the right hand end of the slot M' , the lever E , which so far has been swinging substantially on the point E^2 as a fulcrum, will begin to swing on the point E' since the two arms D, D' and the rod M are practically rigid and stationary in the released position. The pin E^2 will therefore draw the rod G toward the left, swinging the dead lever H in the same direction on its pivot H^2 . This will cause the pin K' to move away from the bearing D^2 and the wedge D will drop by gravity to remain in contact with the pin K' . During the next application of the brakes, the dead lever will therefore at once move the brake beam C' to the right owing to the engagement of the pin K' with the wedge L and to the engagement of the wedge L with the bearing D^2 . It will be seen that the slack is taken up during the application of the brakes and the normal clearance between wheel and brake shoe is restored during the release of the brakes. The slack is taken up by increasing the distance between the brake beams. The lever E always returns to the same release position and this is the reason that the travel of the pin E' sometimes exceeds the length of the slot M' . The entire slack is taken up at one operation, no matter what the extent of the slack may be. It will be understood that during the application of the brakes the pin K' exerts a pressure against the wedge L and there is some danger of the wedges slipping upward on the bearing D^2 . This is the reason I prefer to make the wedge with a roughened end surface L' .

The construction shown in Figs. 2 and 5 is very similar to that illustrated by Fig. 1; the brake beams are solid instead of hollow, and each of them is provided with a bearing C^3, C^4 for the take-up rod M^2 ; instead of the pin and slot connection at the left-hand end of the take-up rod, I have arranged stops M^3 on said rod at the opposite sides of the bearing C^3 , and in order that said stops may be adjusted, I prefer to construct them as nuts screwing on said rod. The distance between these stops would correspond to the intended normal travel of the brake beam C . In all other respects the construction is the same as the first described, and the operation is exactly the same, that is to say, the normal travel of the brake mechanism will have no effect on the position of the take-up rod M^2 relatively to the bearing C^4 . Any excess movement toward the left will cause the rod M^2 to slip in the bearing C^4 and then, when the parts return to their original position, the wedge L will slip down in the same manner as described.

The construction shown in Figs. 3 and 4 differs from those first described only by a slightly modified construction of the slide engaged by the wedge L . This slide K^2 is connected with the pin H^2 of the dead lever H , and has a top flange K^3 to limit its downward movement, and a bottom pit K^4 to limit its upward movement. This slide is arranged between the members of the arm D' , instead of on the outside thereof. The end 100 surface of the slide is directly engaged by the wedge L .

In all the constructions of my invention I deem it advisable to make the arms D, D' rigid and preferably integral with the respective brake beams C, C' and this is shown best in Fig. 5. A very simple and strong construction is thus obtained. Braces or truss rods C^5 may be run from the outer portions of the brake beams to the arms D, D' .

In Fig. 6 the slide K^5 is guided by means of the pin H^2 and also by means of a stem K^6 which engages the wedge L . The slot D^2 of the arm D' is practically of the same length as in Fig. 3 and shorter than in Figs. 1 and 2. The take-up rod will be of the same construction as hereinbefore described, the distance between the brake beams being adjusted automatically if any slack exists.

A similar construction is shown in Figs. 7 and 8, the only difference being that the wedge L is omitted and the rod K^6 passes through a dog N^2 of the same character as the dog N and a spring O' presses against said dog and through its action the lever H and slide K^5 may move toward the left independently of the brake beam C' . The free end of the dog N^2 projects to the outside of the arm D^4 so that the operator may

swing said dog to a position at right angles to the rod K^6 , thereby allowing the rod and the dead lever H to be adjusted to the proper position when the mechanism has been assembled. The sliding movement of the rod K^6 relatively to the dog N^2 will remove any sleet or ice which may stick to said rod assuring an operative condition of the mechanism in winter.

10 The construction shown in Fig. 9 differs from that of Fig. 1 only by the manner of connecting the take-up rod M^4 with the brake beam C' . The take-up rod M^4 is formed with rack teeth M^5 facing in one direction and adapted to be engaged by a spring C^6 which is carried by the bearing C^3 in which the rod M^4 is guided. This construction allows the rod M^4 to slide outward to increase the distance between the brake beams C , C' , 20 but does not allow the rod to move in the opposite direction.

25 The construction in Fig. 10 is similar to that illustrated in Fig. 6. Instead of the wedge L , however, I employ a toothed eccentric dog P fulcrumed at P' and engaging the rod K^6 . In the normal operation this dog will allow the rod K^6 to move toward the left and not toward the right. If, however, it is desired to release the rod for movement in either direction, this may be done by swinging the dog P by means of its handle P' . In all the forms of my invention the dog, wedge or other retaining member can be brought by hand into a releasing position so that the parts may be properly adjusted.

30 In Fig. 11 the rod K^6 carries a number of washers Q which fill the length of the chamber D^5 on the arm D' . When the rod K^6 moves toward the left relatively to the arm D' , those washers Q from which the end of the rod is withdrawn will drop in the chamber D^5 as shown at the right-hand end thereof and will thus become interposed between the end of the rod and the cover D^5 of the chamber. The rod K^6 and slide K^3 will therefore be held rigid with the arm D' at all times as regards any movement toward the right. To release the rod K^6 for adjustment toward the right, the cap D^6 is removed and one or more of the dropped washers are raised until the rod can be inserted in them. In other respects this construction is the same as before described.

35 In Fig. 12 a wedge L has been applied in connection with the arm D and the slide K in connection with the live lever E . On this live lever I have further mounted a pawl R weighted at one end so that it will be kept in engagement normally with a rack D^7 on the arm D . The dead lever H has a fixed pivotal connection H^2 with the arm D' . In this particular construction in the application of the brakes the lever E swing-

ing toward the left about its end E^3 will, through the medium of the pawl R , carry the brake shoe B' into engagement with the wheel A . Then and practically simultaneously, the lever E , by swinging on the point E^3 , will bring the brake shoe B' against the wheel A' . During this movement if there is any slack in the apparatus so that the lever E is to exceed its normal travel, the pawl R will be carried toward the right 75 sufficiently to engage it with a new tooth of the rack D^7 , or, in other words, the distance between the brake beams C , C' will be increased with the same purpose and effect as previously described. The normal travel of 80 the pawl R is less than the distance between the two adjacent teeth of the rack D^7 . When the brakes are released and the lever E swings toward the right, the normal clearance will be restored, and as soon as the 85 brake beams have returned to their normal positions the point of the pawl R will form a fulcrum on which the live lever E will swing, if its movement exceeds the normal travel, so that in this case the slide K will 90 move toward the right, and the wedge L will slide down on the inclined bearing D^3 .

95 In each of the constructions shown, the operating rod F will return to exactly the same position when the brakes are released. To assist this return movement, a coiled spring S may be employed, see Fig. 9.

100 It will be observed that the device or shim which holds the pivotal connection between the brake lever H and the corresponding brake shoe in its shifted position (that is, the wedge L of Figs. 1, 2, 3, 6 and 9, the dog N^2 of Figs. 7 and 8, the cam P of Fig. 10, and the washers Q of Fig. 11), and the pawl R which holds the pivotal connection 105 between the brake lever E and the corresponding brake shoe (Fig. 12), are separated and disconnected from the said respective levers, so that said device or shim, as the case may be, may be moved independently 110 of the lever as in the case of the wedge by knocking the wedge upward by means of a suitable tool. This device or shim may therefore be brought into a releasing position by hand or otherwise without changing 115 the position of the brake lever held thereby.

I claim—

1. In a vehicle brake, two brake shoes adapted to engage adjacent wheels in combination with levers, one for each of said shoes, one of said levers having a permanent pivotal connection with its shoe and the other having a pivotal connection which is adjustable relatively to its shoe, a wedge arranged to automatically drop to a new position whenever the connection of said other lever is shifted and means connected with one of said levers for returning the levers to normal position. 120

2. In a vehicle brake, two brake shoes 125

- adapted to engage adjacent wheels, in combination with levers, one for each of said shoes, one of said levers having a pivotal connection which is adjustable relatively to its brake shoe, a wedge arranged to automatically drop to a new position whenever the connection of said lever is shifted and means connected with one of said levers for returning the levers to normal position.
- 10 3. In a vehicle brake, two brake shoes adapted to engage adjacent wheels, in combination with levers, one for each brake shoe, a slide movable relatively to one of the brake shoes and pivotally connected with the corresponding lever, an inclined surface facing said slide and permanently connected with said brake shoe, and a wedge engaging said surface at one side and the slide at the other side and arranged to drop by gravity when required, so as to always fill the space between the slide and said inclined surface.
- 15 4. In a vehicle brake, brake beams and shoes carried thereby, in combination with an adjustable connection by which the distance between the brake beams may be varied, said connection including levers, one for each brake beam, a slide connected with one of said levers and movable relatively to its brake beam, a wedge movable on said 20 brake beam transversely to the slide's path to hold the slide against movement in one direction and means connected with one of said levers for returning the levers to normal position.
- 25 5. In a vehicle brake, two brake shoes adapted to engage adjacent wheels in combination with an adjustable connection by which the distance between the brake shoes may be varied, said connection including levers, one for each brake shoe, the connection of one of said levers being adjustable relatively to its brake shoe, a wedge arranged to shift to a new position by gravity whenever the connection of said lever is shifted and 30 means connected with one of said levers for returning the levers to normal position.
- 35 6. In a vehicle brake, two brake shoes adapted to engage adjacent wheels, in combination with an adjustable connection by which the distance between said shoes may be varied, said connection including levers, one for each brake shoe, a slide connected with one of the levers and movable relatively to its brake shoe, a wedge movable transversely of the slide's path to hold it against movement in one direction and means connected with one of said levers for returning the levers to normal position.
- 40 7. In a vehicle brake, two brake shoes adapted to engage adjacent wheels, in combination with levers, one for each brake shoe, a slide movable relatively to one of the brake shoes and pivotally connected with the corresponding lever, an inclined surface facing 45 the slide and permanently connected with
- said brake shoe and a wedge movable by gravity transversely of the slide's path and engaging said surface at one side and the slide at the other side.
8. In a vehicle brake, the combination of 70 brake shoes and an adjustable connection between them with brake levers, one of which has its connection with the corresponding brake shoe adjustable toward and from said shoe, and a holding device for 75 normally preventing the movement of the said last named connection relatively to the brake shoe in one direction, said device being disconnected from and separate from the lever mechanism, so that said holding 80 device may be moved into a releasing position by hand or otherwise without affecting the position of said lever.
9. In a vehicle brake, two brake shoes adapted to engage adjacent wheels, in combination with an adjustable connection by which the distance between said shoes may be varied, said connection including levers, one for each brake shoe, a slide connected with one of the levers and movable relatively to its brake shoe, and a shim movable by gravity transversely of the slide's path to hold it against movement in one direction.
10. In a vehicle brake, brake beams provided with arms integral with the beams 95 and projected therefrom in opposite directions, a brake applying mechanism which includes levers pivotally connected with said arms, the pivotal connection of one of said levers being adjustable lengthwise of the corresponding arm, means for normally preventing movement of said pivotal connection lengthwise of said arm in one direction and means connected with one of said levers for returning the levers to normal position.
11. In a vehicle brake, two brake shoes in combination with an adjustable connection therebetween by which the distance between the shoes may be varied, said connection including levers, one for each brake shoe, a 100 slide connected with one of the levers and movable relatively to its brake shoe, and a shim movable by gravity transversely of the slide's path to hold it against movement in one direction.
12. In a device of the character described, in combination, a plurality of wheels, brake shoes adapted to coat with said wheels, a live lever, a dead lever, a rod connected with the lower ends of said levers, a member arranged automatically to move to a new position whenever the fulcrum of said live lever is shifted to hold the slack taken up, and means connected with one of said levers for returning the parts to normal position.
13. In a device of the character described, in combination, a plurality of wheels, brake shoes coating with said wheels, live and dead levers connected with the brake shoes, a movable fulcrum member for said live

- lever, and a take-up member positioned between the movable fulcrum and a relatively fixed part of the brake rigging arranged to drop by gravity to fill the space between the 5 movable fulcrum and the fixed part as the slack due to the wear of the parts is taken up.
14. In a device of the character described, in combination, a plurality of wheels, brake 10 shoes adapted to coact therewith, live and dead levers, connecting means between the lower parts of said levers, adjusting means by which the distance between the brake shoes may be varied to take up the slack 15 due to the wear of the parts, comprising a movable fulcrum on one of said levers, and a gravity actuated member arranged to shift to a new position when the fulcrum of said lever changes.
15. In a device of the character described, in combination, a plurality of wheels, brake 20 shoes adapted to coact therewith, live and dead levers, connecting means between the lower parts of said levers, adjusting means 25 by which the distance between the brake shoes may be varied to take up the slack due to the wear of the parts, comprising a movable fulcrum on one of said levers, a member arranged to shift to a new position when 30 the fulcrum of said lever changes, and means connected with one of said levers for returning the parts to normal position when the brakes are released.
16. In a device of the character described, 35 in combination, a plurality of wheels, brake shoes adapted to coact therewith, live and dead levers, a movable fulcrum for one of said levers, a fixed abutment, an inclined surface on one of said parts, and a wedge 40 movable by gravity transversely of the path of travel of the movable fulcrum to coact with the inclined surface whereby the slack due to the wear of the parts is permanently taken up.
17. In a device of the character described, 45 in combination, a plurality of wheels, brake shoes adapted to coact therewith, live and dead levers connected with the brake shoes, one of said levers, having a movable fulcrum, a ratchet on the connection between the lever and the brake shoe each tooth of which is substantially equal to the desired amount of clearance between the brake shoes and the wheels when the brakes are released, 50 and a pawl carried by one of said levers adapted to coact with said ratchet to hold the fulcrum and the lever in its new position as it shifts to take up the slack due to the wear of the parts.
18. In a device of the character described, 55 in combination, a plurality of wheels, brake shoes adapted to coact therewith, live and
- dead levers pivotally connected with the 65 brake shoes, one of said levers having a movable fulcrum, a ratchet on the connection between the lever and the brake shoe each tooth of which is substantially equal to the desired amount of slack between the 70 brake shoes and the wheels when the brakes are released, a pawl carried by one of said levers adapted to coact with said ratchet to hold the fulcrum and the lever in its new position as it shifts to take up the slack due to the wear of the parts, and means adapted 75 positively to prevent a retraction of the lever to its former position.
19. In a device of the character described, in combination, a plurality of wheels, brake 80 shoes adapted to coact therewith, live and dead levers pivotally connected with the 85 brake shoes, one of said levers having a movable fulcrum, a ratchet on one part each tooth of which is substantially equal to the desired amount of slack between the 90 brake shoes and the wheels when the brakes are released, a pawl carried by another part adapted to coact with said ratchet to hold the fulcrum and the lever in its new position as it shifts to take up the slack due to the wear of the parts, and means adapted 95 positively to prevent a retraction of the lever to its former position, said means comprising a gravity actuated wedge.
20. In a device of the character described, 100 in combination, a plurality of wheels, brake shoes adapted to coact therewith, brake beams, live and dead levers pivotally supported thereby, one of the pivots being movable to take up the slack due to the wear of the parts, a ratchet on the supporting member, and a pawl on the lever adapted to coact with said ratchet to take up and hold the slack.
21. In a device of the character described, 105 in combination, a plurality of wheels, brake shoes adapted to coact therewith, brake beams, live and dead levers pivotally supported thereby, one of the pivots being movable to take up the slack due to the wear of the parts, a ratchet on the supporting member, and a pawl on the lever adapted to coact with said ratchet to take up and hold the slack, the distance between the teeth of 110 said ratchet being substantially equal to the desired clearance between the wheels and the brake shoes when in released position.

In testimony whereof I have signed this specification in the presence of two subscribing witnesses.

WILLIAM H. SAUVAGE.
